PROCESS FOR TREATING
HYDROCARBON OILS

Walter A. Schulze and Lovell V. Chaney, Bartlesville, Okla., assignors to Phillips Petroleum Company, Bartlesville, Okla., a corporation of Delaware

No Drawing. Application June 20, 1933,
Serial No. 676,762

5 Claims. (Cl. 196—24)

This invention relates to improvements in the method of treating hydrocarbons and the like with alkali polysulfides and/or certain alkaline earth polysulfides. In particular, it relates to the removal of elementary sulfur from petroleum and coal tar hydrocarbon liquids and similar substances by means of sodium, potassium and ammonium polysulfides.

It has for its primary purpose the removal of elementary sulfur from petroleum and naphthas, natural gasolines, petroleum hydrocarbons fractions and other petroleum oils, benzol, solvent naphtha, and other coal tar products, and from other sulfur-containing solvents responding to such treatment.

The presence of elementary sulfur in motor fuels and other petroleum products is objectionable on account of the tendency of elementary, or free, sulfur to react with certain metals, particularly at elevated temperatures, and to produce other corrosive substances when burned in internal combustion engines. Recognition of this tendency is at present exemplified by the rigid specifications included in the U. S. motor gasoline specifications (U. S. Bureau of Mines Technical Paper 323 B), wherein the requirements for passing the so-called "corrosion test" specify no discoloration of a clean copper strip after three hours submersion in the fuel under test at a temperature of 50° C. (122° F.). This test is sensitive to approximately 0.005 per cent elementary sulfur in the material tested.

The method of treatment described in the present invention removes elementary sulfur from such types of motor fuels, and many other sulfur-containing solvents, to the extent that they will respond negatively not only to the above-mentioned corrosion test, but also to a test sensitive to 0.00004 per cent of elementary sulfur.

The ability of alkali mono-sulfides to combine with elementary sulfur to form polysulfides is well known, as may be found in almost any inorganic chemistry text-book. Mellor, for instance, very ably discusses this subject in his "Inorganic and Theoretical Chemistry" vol. II, p. 629 et seq., Longmans, Green and Company, 1927.

Sodium mono-sulfide, (Na₂S), has been used for removing elementary sulfur from various solvents therefor, usually at more or less elevated

temperatures. Potassium mono-sulfide accomplishes this result much more readily than does sodium mono-sulfide, and at lower temperatures. At present, the latter method is handicapped commercially due to cost factors.

Cobb (U. S. Patents 1,300,816 and 1,413,005) uses alkali and alkaline earth mono-sulfides to remove sulfur from petroleum hydrocarbons at temperatures from 160° to 190° F. He may also use alkali and alkaline earth hydroxides to accomplish his purpose where the material being treated also contains hydrogen sulfide, again working at quite elevated temperatures.

Alkali polysulfides have heretofore never been utilized in treating liquids of the character hereinbefore enumerated in such a manner as to make the method commercially practicable; that is, no disclosure has heretofore been made of a rapid and inexpensive method for quickly and completely removing dissolved elementary sulfur from sulfur-containing solvents at ordinary atmospheric temperatures. By ordinary atmospheric temperatures are meant temperatures between approximately 40° and 90° F. We have succeeded in accomplishing these results with alkaline polysulfide solutions, the substantiating data and preferred methods of operating being hereinafter set forth.

We have determined that sodium polysulfides, as typical of the alkali polysulfides, rapidly and completely remove elementary sulfur from hydrocarbon solvents at ordinary atmospheric temperatures (40° to 90° F.) when the composition of the polysulfide is approximately between Na₂S_{1.1} and Na₂S₄, the most rapid removal occurring with sodium polysulfides whose compositions are approximately represented by Na₂S₂ and Na₂S₃, and those of intermediate sulfur content. Sodium polysulfides with smaller amounts of sulfur in combination than represented by Na₂S_{1.1} also remove elementary sulfur quantitatively but somewhat more slowly, the time and extent of agitation or contacting for complete sulfur removal becoming considerably greater as the composition of the polysulfide approaches Na₂S, where the sulfur is not completely removed even though contacted as much as 80 to 100 times as long as with similar concentrations of Na₂S_{2.5} or Na₂S₃, for instance, which completely remove the sulfur.

As examples of the relative speeds with which several sodium polysulfides remove elementary sulfur (to less than 0.00004 per cent) from a petroleum hydrocarbon fraction composed principally of heptanes, the following are cited:

ing the desulfurizing effectiveness of the solution. An atmosphere of air oxidizes the polysulfides quite rapidly, and while it is not absolutely necessary to prevent access of air or other oxidizing substance to the solutions, it is advantageous

¹ All polysulfide solutions prepared by adding the required amount of elementary sulfur for a given polysulfide to a sodium monosulfide solution containing 145 g. of Na₂S per liter.

45

The amount of sulfur in the solvent therefore may vary considerably without appreciably altering the speed of its removal with polysulfide solutions.

While the concentration of Na₂S in the sodium monosulfide base solution from which the polysulfides are prepared may vary over a wide range without materially affecting the activity of the resulting polysulfide treating solution, it is preferred to use a base solution with about the same Na₂S concentration as employed in preparing the polysulfide solutions used in obtaining the data shown in the above table. This base solution was prepared by dissolving Na₂S·9H₂O in a minimum amount of water and the solution adjusted by dilution so that each liter of solution contained 145 g. of Na₂S. The concentration of Na₂S in the base solution may be increased up to 200 g. per liter, or the solution may be employed with Na₂S concentrations of the order of 50 to 75 g. per liter.

Weighed amounts of elementary sulfur are added to the sodium sulfide solution to produce the polysulfide desired. With occasional agitation, the sulfur readily dissolves in the sodium sulfide solution at atmospheric temperature. Raising the temperature of the polysulfide solutions is avoided due to rapid conversion of the polysulfides to thiosulfate, or otherwise destroy-

that such oxidizing agents be absent or at a minimum, particularly during agitation of the treating agents with the sulfur-containing solvents, for the effectiveness and longevity of the treating agent is thereby greatly increased.

The presence of a substantial excess of alkalinity is also desirable and preferable in the treating solution, although this is not necessary for the method to be operable. We obtain this alkalinity with a somewhat concentrated alkali hydroxide, an approximately 30° Bé. sodium hydroxide solution having been employed successfully for this purpose in our method. A preferred concentration of excess alkalinity is of the order of 150 g. of NaOH per liter, although the method is operable with little or no added alkalinity, that furnished by Na₂CO₃ sufficing, or with quite high concentrations of NaOH; for example, 300 to 500 g. per liter.

It is desirable to work with treating solutions fairly concentrated in polysulfides. While we prefer to operate with treating solutions containing about 85 g. per liter of Na₂S_{1.5}, 100 g. per liter of Na₂S₂ or 130 g. per liter of Na₂S₃, as examples, the method accomplishes very good results with concentrations varying, for instance, from 15-20 g. per liter of Na₂S_{1.5} to 200-250 g. per liter; and from 20-30 g. per liter of Na₂S₃ to 250-300 g. per liter.

It is advantageous to conduct the treating operation at atmospheric temperatures, which may be taken as 40° to 90° F. Temperatures as low as 32° F. and as high as 130-140° F. may be employed, but such high temperatures should be avoided, if possible, due to the tendency of the polysulfides to lose their desulfurizing qualities at these elevated temperatures. Should the material to be treated have a temperature in the range of 100° to 140° F. when it arrives at the polysulfide treating stage, we prefer to let the material cool to, or artificially bring the temperature to, at least 80° or 90° F. before treating with the polysulfide solution.

During the preparation and storage of the polysulfide solutions, the temperature of the solutions is kept well below 90° F., artificial cooling being resorted to when necessary.

It is highly desirable, and we prefer, to treat with these polysulfide solutions in the absence of air or other oxidizing agent, or in the presence of a minimum amount of them. An atmosphere of inert or non-oxidizing gas may be provided during the operation of the treating process, and during preparation and storage of the polysulfide solutions.

In treating natural gasoline, refinery gasoline, petroleum hydrocarbon fractions, coal tar distillates or other elementary sulfur-containing solvent responsive to our desulfurizing method, one preferred mode of operation is to very intimately contact the material containing the dissolved sulfur with the polysulfide solution, the contacting being accomplished by any of the well known means and may be either batch or continuous. The more intimate the mixing or contacting, the more quickly and completely will the treating agent perform the sulfur removal. Following the contacting, the treating agent is separated from the material treated by settling and decantation.

By way of illustration, a treating solution containing Na₂S₂ is prepared by dissolving a commercial grade of sodium sulfide in a minimum amount of water, adjusting the solution (from analysis or calculation) to an approximate concentration of 150 g. of Na₂S per liter (1.25 lb. per gallon) and adding 60 g. of elementary sulfur per liter (0.5 lb. per gallon); and agitating gently at 40° to 90° F., with a minimum or no access of air, to effect solution of the sulfur. The resulting polysulfide will have a composition approximating the disulfide, Na₂S₂. Approximately an equal volume of 30° Bé. sodium hydroxide is mixed with the resulting solution, observing the same moderate temperatures and non-oxidizing atmosphere, and the treating solution is ready to remove elementary sulfur from hydrocarbon oils and the like. The substances comprising this treating solution will be present in approximately the following concentrations:

Na₂S₂, 106 g. per liter
NaOH, 150 g. per liter

For a treating solution prepared in a similar manner, but containing sufficient sulfur to form the polysulfide Na₂S₃, the concentrations of the comprising substances would be approximately:

Na₂S₃, 137 g. per liter
NaOH, 150 g. per liter

Potassium and ammonium polysulfides may be used instead of sodium polysulfides, either alone or in admixture with their corresponding hydroxides or with sodium hydroxide. Their rela-

tive efficiencies as desulfurizing means are shown by the following tabulation:

Polysulfide treating solution, 10 volumes	Time for complete sulfur removal from 60 volumes solvent containing 0.143 percent sulfur	5
Na ₂ S ₂ (NaOH).....	28 seconds.	
K ₂ S ₂ (KOH).....	60 seconds.	
(NH ₄) ₂ S ₂ (NH ₄ OH).....	60 seconds. ¹	10

¹ Over 99 percent removed.

The polysulfide treating solutions above are practically equivalent with reference to sulfide concentration and to the amount of corresponding hydroxide contained in each. With NaOH instead of NH₄OH incorporated into the (NH₄)₂S₂ solution, the sulfur was totally removed in less than 60 seconds.

Calcium and barium polysulfides also exhibit considerable desulfurizing effects, CaS₂ and BaS₂ solutions, for example, in the presence of solid Ca(OH)₂ and/or Ba(OH)₂ completely removing the elementary sulfur from hydrocarbon liquids in 2 to 4 minutes. In the presence of solid Mg(OH)₂, magnesium polysulfides remove elementary sulfur but do so quite incompletely.

Certain substances occurring in some gasolines tend to retard the above described desulphurizing action of alkaline polysulfides. Some oxygenated bodies, such as unsaturated aldehydes, for instance, possess this retarding tendency, and while the complete removal of elementary sulfur from a given solvent for the sulfur is retarded, considerably in some cases, it is by no means impossible to extract the sulfur with the polysulfides. A longer contacting period suffices to accomplish the removal. Furthermore, the retarding effect of such oxygenated bodies may often be lessened by contacting the sulfur-containing oil prior to the polysulfide treatment with a solution of a caustic alkali which may or may not contain a suitable reducing agent such as sodium stannite or the like.

From the foregoing it is believed that the steps and advantages of the process may be readily understood by those skilled in the art, and it is manifest that changes may be made in the details disclosed, without departing from the spirit of the invention, as expressed in the claims.

What is claimed and desired to be secured by Letters Patent is:

1. The process for removing elementary sulfur from petroleum oils, which comprises as the initial step, contacting the oil containing elementary sulfur at atmospheric temperature with an aqueous solution of a polysulfide lower than the tetrasulfide selected from the group consisting of the alkali and alkaline earth polysulfides, and separating the oil from the treating solution.

2. The process for removing elementary sulfur from petroleum oils, which comprises as the initial step, contacting the oil containing elementary sulfur at substantially atmospheric temperature with an aqueous solution of sodium polysulfides lower than the sodium tetrasulfide, and separating the oil from the treating solution.

3. The process for removing elementary sulfur from petroleum oils, which consists of briefly contacting the oil containing elementary sulfur at substantially atmospheric temperature with an aqueous solution of sodium disulfide, and separating the oil from the treating solution.

4. In the process for removing elementary sul-

fur from petroleum oils the step which consists in initially contacting the oil containing elementary sulfur at substantially atmospheric temperature with an aqueous solution consisting of sodium hydroxide and a sodium polysulfide lower than the tetrasulfide, and separating the oil from the treating solution.

5. The process for removing elementary sulfur from petroleum oils which comprises as the initial

step contacting the oil containing elementary sulfur at substantially atmospheric temperature with an aqueous solution of sodium polysulfide of the formula Na_2S_x in which x is not less than 1.1 or greater than 4, and separating the oil from the 5 treating solution.
